UNITED STATES PATENT OFFICE

HERMON LEON AND JACK WOLF LEON, OF ATLANTIC CITY, NEW JERSEY

SELF-LIGHTING CIGARETTE

Application filed March 15, 1929. Serial No. 347,364.

This invention relates to self lighting cigarettes and the like and is an improvement on the invention disclosed in our pending application serially numbered 229,441, dated December 28th, 1927.

In said application igniting means for the tobacco or smoking material of cigarettes are provided which include inflammable material placed in contact with the tobacco, and, also in contact with a cigarette, an igniting substance, so that when the latter is drawn from the cigarette against the inflammable material, flame is produced to light the cigarette.

As the inflammable and igniting materials are, in such an arrangement, in mutual contact, we find it desirable to place these materials in spaced relation with each other, so that initial contact is not effected until the igniting substance is operated for igniting purposes.

The primary object of the invention is therefore the provision of a lighting unit for cigars, cigarettes or other smoking rolls in which the inflammable and igniting elements are spaced apart, so that a cigarette carrying the lighting unit may be manipulated freely or carried in any ordinary manner without danger of accidental ignition.

Another object of the invention is to utilize the tobacco or smoking material of a cigarette for forcing at the proper time the igniting substance, which is carried on a flexible strip, into positive contact with the inflammable material, the latter being embedded in the tobacco, when the strip is drawn from the cigarette to light the same.

A further object of the invention is to provide an igniting unit of the class described with a manipulating tab which is at all times easily accessible. The unit may be mounted about the center of the end disk applied to the cigarette, with the tab projecting part of the way to the outer edge of the disk, thereby providing a compact and serviceable self lighting cigarette.

With these and other objects in view, the invention resides in certain novel construction and combination and arrangement of parts, the essential features of which are

hereinafter fully described, are particularly pointed out in the appended claims, and are illustrated in the accompanying drawing, in which:

Figure 1 is a perspective view of a cigarette having my improved igniting unit attached thereto. 55

Figure 2 is a vertical longitudinal section of one end of the cigarette shown in Figure 1.

Figure 3 is a horizontal sectional view of 60 the same end on the line 3-3 of Figure 2.

Figure 4 is a perspective view of an attaching strip carrying the inflammable element.

Figure 5 is a perspective view of a strip 65 carrying the igniting element.

Figure 6 is a view showing a method of withdrawing the igniting element to light the smoking article. 70

In the particular embodiment of the invention selected for illustration in the drawings, the numeral 10 designates a complete cigarette with an igniting unit A, the latter comprising an attaching strip 11 of paper or other suitable material, the respective tapered ends 12 of which are attached by an adhesive to the opposite sides of the outer wrapping of the cigarette at one of the ends thereof. 75

We find it advantageous to construct the 80 combustible element 13 of a substance having potassium chloride as a base and which is mounted on one side of the strip 11. The element 13 is substantially triangular in cross section with its apex 14 embedded in the tobacco 15. At one of its ends 16 a flexible strip 17, which may be of any appropriate material, carries the igniting substance 18, while the other end of said strip forms a manipulating tab 19. 85

Before inserting the element 13 in the material 15 the strip 17 is placed in the required position with the igniting friction material 18 on the exterior of the bridge portion 20 of the strip 11, the tab 19 overlapping the end 16, thereby positioning said material 18 in spaced relation with the combustible element 13. The material used in the respective combustible and igniting elements may be the same as those detailed in 95 100

my said pending application. The phosphorus is adhesively secured to the strip and the outer particles remain free thereon.

It will be seen on inspection of the drawings, that the tab 19 is easily accessible as it extends beyond the side of the cigarette, and that even when the tab becomes lodged against the tobacco 15, as may be the case when packed, said tab is still easy to seize and operate. The inner part of the tab 19 is adhesively secured at 17' to the end 16 to normally hold the same flat adjacent the end of the cigarette. Before drawing the strip 17 to light the cigarette, the ends 16 and 19 may be partly straightened out by breaking the adhesive bond, as shown in Figure 6, to facilitate removal of said strip. As the latter moves past the combustible element 13 ignition is readily effected, partly because of the pressure maintained by the tobacco 15 on the moving strip. Removal of this strip places the ignited element 13 in direct contact with said material.

In this manner a safe and novel means for lighting inflammable material is provided, since the latter material is preserved free from the substance 18 until removal of the strip 17 has been started. Withdrawal of this strip may be by a quick and jerky movement, or withdrawal may be effected gradually, as becomes apparent by viewing Figure 6 of the drawings.

It is customary among smokers before lighting a cigarette to tap one end of the same on some convenient flat object to partly remove the smoking material 15 from the opposite end. This custom has the additional useful effect, with a cigarette having my igniting unit A thereof, on compressing the material 15 against the edge 14 to further facilitate ignition.

Cigarettes of this kind may be put up in the usual packages or cases, and, in order to utilize existing forms for constructing these cases or containers, cigarettes of slightly less longitudinal dimension may be manufactured, since the unit A may project slightly beyond the end 21, as illustrated, in order that the length of the cigarette 10 with said unit attached thereto may be identical with that of a cigarette as heretofore manufactured. The lighting unit may be more deeply embedded in a cigarette than in the article 10 illustrated, thereby bringing about the same result, without departing from the invention.

While we have described what we deem to be the most desirable embodiment of our invention, it is obvious that many of the details may be varied without in any way departing from the spirit of our invention; and we desire it to be understood that we may make changes in the construction and in the combination and arrangement of the several parts, provided that such changes

fall within the scope of the appended claims.

What is claimed as new is:—

1. In an igniting unit for a cigarette comprising a combustible element projecting into the body of a cigarette, a flexible strip wound about said element, and a friction substance on said strip for frictional contact with said combustible element when pulled from a wound condition. 70

2. In an igniting unit for a cigarette comprising a combustible element partly projecting into the body of a cigarette, supporting means for said element, a flexible manipulable strip wound about said element and having a central portion interposed between said element and said material, and a friction substance provided on the inner wound end of said strip for frictional wiping contact with said combustible element. 80 85

3. In an igniting unit for a cigarette comprising an attaching strip bridging one end of a cigarette, a combustible element on the inner face of said strip, said element partly projecting into the body of the cigarette, an igniting element comprising a flexible strip wound about said attaching strip, and a friction substance provided on one terminal of said flexible strip, said friction substance adapted to be removably seated on the outer surface of said attaching strip, with the other terminal left free to be manually pulled. 90 95

4. In an igniting unit for a cigarette having compressed smoking material therein, a strip attached to one end of the cigarette and bridging the same, a triangular shaped combustible element on the inner face of said strip, the apex of said triangular shaped element projecting into said smoking material, and a flexible strip having a portion interposed between said element and said smoking material, one terminal on said flexible strip being provided with a friction substance and being removably seated on the outer surface of said first strip, while the other end of said flexible strip is free, so that when said latter end is operated to withdraw said friction substance the same is urged by said smoking material against the apex of said combustible element to ignite the latter for lighting said smoking material. 100 105 110 115

5. In combination with a cigarette, a strip bridging one end of said cigarette and fixedly secured thereto, a combustible substance provided on one side of said strip and embedded in the tobacco body of said cigarette, a flexible pull strip, an igniting substance provided on one side and at one end of said pull strip, said pull strip being wound about said first strip with the igniting substance disposed against the exterior side of said first strip out of contact with 120 125 130

said combustible material, while the outer free end of said pull strip overlaps its opposite inner end and is adhesively secured thereto, substantially as and for the purpose specified.

5 In testimony whereof we have affixed our signatures.

HERMON LEON.
JACK WOLF LEON.
